HOT WATER TANK ASSEMBLY

William E. Crawford, Wauwatosa, Wis., assignor
to A. O. Smith Corporation, Milwaukee, Wis.,
a corporation of New York

Application May 18, 1942, Serial No. 443,437

2 Claims. (Cl. 228—64)

This invention relates to a hot water tank assembly and more particularly to the assembly of the head and shell of a tank that is lined with ceramic enamel or other corrosion resistant material for protection against corrosive action by the fluid contained in the tank in service.

The principal object of the present invention is to provide a hot water tank assembly in which corrosive disintegration by the contained fluid of the weld metal of the joint between parts is precluded by providing an improved fluid tight joint that prevents circulation of the fluid to the weld.

Another object is to provide an assembly of a hot water storage tank in which the joints are specially reinforced to prevent rupture.

Other objects will appear from the following description of embodiments of the invention illustrated in the accompanying drawing.

In the drawing:

Figure 1 is a longitudinal section through a hot water tank embodying the invention;

Fig. 2 is an enlarged section through a joint between the upper head and body of the tank;

Fig. 3 is an end view of a head and shell assembled together; and

Fig. 4 is a section similar to Fig. 2 and showing a modified embodiment of the invention.

Referring to the drawing there is illustrated a hot water storage tank having a shell 1, an upper head 2 and a lower head 3. The description hereafter is limited to the manner of joining the upper head 2 to the shell 1, it being understood that the description equally applies to the manner of connecting the head 3 and shell 1.

The shell 1 has a generally cylindrical shape and is fabricated from sheet metal of a strength and thickness suitable to resist the pressure exerted by contained fluid when the tank is in service. The ends of the shell 1 are outwardly flared in the fabrication operation to provide the substantially straight outwardly extending flanges 4 and 5 lying in a plane at right angles to the axis of the shell.

The interior surface of the shell, including the inner surface of the flanges 4 and 5, is provided with the corrosion resistant lining 6. This lining may be of any suitable material that has the corrosion resistant qualities desired but preferably consists of ceramic enamel frit that is applied to the tank surface exposed to the contained fluid and then fused thereto by heating the shell to the firing temperature of the enamel.

The upper head 2 is preferably formed in a

convex shape and is made from steel or other metal similar to that employed in the shell 1.

The head 2 is provided at its skirt portion with the substantially straight outwardly extending flange 7 that corresponds in diameter and direction with the flange 4 of the shell 1.

The interior surface of the head 2, including the inner surface of the flange 7, is covered with the corrosion resistant lining 8. As in the case of the lining 6 of the shell 1, the lining 8 is preferably of a ceramic enamel material specifically adapted to resist the corrosive action of contained fluid and it is applied and fused in the same manner as lining 6.

After the head 2 and the shell 1 have been completed as described they are ready for assembly. In the assembling operation the head 2 is first disposed in axial alignment with the shell 1 and the two are brought together with their flanges in circumferential alignment so that the lining 8 on the flange 7 engages the lining 6 of the flange 4. While the head 2 is held in tightly fitting position with respect to the shell 1, weld metal 9 is circumferentially deposited, preferably by electric arc welding, at the outer edges of the flanges 4 and 7 of the shell and head to join these members together into an integral structure.

The flanges of the head and shell provide a relatively large area in which the lining 6 of the shell and lining 8 of the head overlap each other for a substantial distance to effectively seal the approach to the weld metal 9 by the liquid contained within the tank.

The substantially thin gasket 10 of corrosion resistant material such as asbestos, glass fiber or soft metal may be disposed between the flanges of the head and shell to additionally seal the approach to the weld 9. If the gasket 10 is employed it may be assembled with the tank by applying it to the flange 4 of the shell and then holding it in place until the flange 7 of the head is pressed into position. The making of the weld 9 securely holds the gasket between the flange 4 of the shell and flange 7 of the head.

In place of the gasket 10, it is possible to seal the linings of the flanges together by interfusing the same, preferably prior to welding, in the manner described in applicant's co-pending application Serial No. 443,438, filed on even date herewith.

If no further support were given the joint between the head and shell of a tank assembled in the manner described, there is likelihood of a rupture of the joint in service. The internal

pressure of the fluid in service tends to move the head away from the shell with a resultant opening of the joint therebetween.

To prevent the opening of the joint in this manner and to maintain the tight engagement between the overlapping flanges of the head 2 and shell 1, the hoop or clamp 11 is provided.

It is preferred that the hoop 11 be composed of two parts, each part forming a semicircle around the circumference of the tank. The hoop 11 has a jaw-shaped channel cross section with the closed web on the outer circumference of the hoop and the open flange edges shaped to conform to the approach of the wall of the tank to the flanges 4 and 7. The hoop is stressed in such a manner as to produce a predetermined pressure when forced over the ring formed on the outside wall of the tank by welding the flanges 4 and 7 together.

In assembling the hoop 11 with the tank, the two respective parts of the hoop are forced over the ring formed by the flanges 4 and 7 and then the ends of the parts of the hoop are welded together by the welds 12 as illustrated in Fig. 3. The welds 12 may be made by any suitable method of welding and serve to hold the hoop 11 in tight engagement around the circumferential joint between the head and shell.

The hoop 11 exerts an inwardly axially directed clamping pressure that is predetermined to be sufficient to offset and overcome the outwardly axially directed pressure of the contained fluid. This prevents the joint between the head and shell from being sprung open. The lining 6 of the shell is held in tight overlapping engagement with the lining 8 of the head and the contents of the tank are prevented from flowing in contact with the weld 9. The hoop 11 also operates in the same manner in the event that the gasket 10 is employed between the flanges of the head and shell.

Lugs may be employed instead of the hoops 11 to provide the clamping pressure desired at the joint between the head and shell or as shown in Fig. 4 illustrating another embodiment of the invention, the clamps 13 may be utilized to perform the clamping function.

The clamps 13 may be formed with a shape similar to the hoops 11 to fit the contour of the outside of the tank at the joint between the head and shell. The clamps, however, consist of two separate ring parts, one being disposed below the welded flanges and the other part being disposed above the flanges. The inwardly directed axial pressure is provided in the clamps by employment of the bolts 14 disposed slightly removed from the weld 9 to bolt together the two parts of the clamp and to maintain the flanges 4 and 7 of the shell and head in tight overlapping engagement.

The invention has been specifically described as applied to the joining of the heads and shells of hot water tanks. It is, however, well adapted

to be employed in joining half shells together or with any other form of container where it is necessary to utilize means to counteract pressure directed axially outwardly perpendicular to a joint between two members.

The invention provides a relatively large size tank for weight of metal employed as compared to other tanks where special fabrication methods have been employed to provide a strong joint between a head and shell with often a considerable sacrifice of space in the tank. The invention also provides a strong, durable joint that is doubly strengthened against rupture by employment of a circumferential weld in combination with clamping means to hold the head and shell together.

Various embodiments of the invention may be employed within the scope of the accompanying claims.

I claim:

1. A hot water tank assembly comprising a generally cylindrical shell having an outwardly extending flange at its end portion and a corrosion resistant lining of ceramic enamel to protect the same against corrosion in service, a head similarly lined and having an outwardly extending flange at its skirt portion similar to that of the flange on said shell, the flange of the head being supported over a substantial overlapping area by the flange of the end portion of said shell, a circumferential weld joining said flanges at their circumferential edges and sealing the lining of the flange of the shell against the lining of the flange of the head in said overlapping area to prevent circulation of fluid to the metal at the joint, and a hoop disposed to clamp said flanges against deflection and prevent separation of the overlapping linings at the joint by pressure directed axially outwardly against the head of said tank by the contained fluid.

2. A hot water tank assembly comprising a generally cylindrical shell having an outwardly extending flange at its end portion and a corrosion resistant lining of ceramic enamel to protect the same against corrosion in service, a head similarly lined and having an outwardly extending flange at its skirt portion similar to that of the flange on said shell, the flange of the head being supported over a substantial overlapping area by the flange of the end portion of said shell, a corrosion resistant filler material disposed in the overlapping area between the flanges of the head and shell in tight engagement therewith, a circumferential weld joining the head and shell integrally together and sealing the said filler material in the joint therebetween, and a hoop disposed to clamp said flanges axially inwardly by a predetermined pressure to prevent injury to the enamel by deflection of said flanges and counteract the outwardly directed axial pressure exerted against the head of the tank by the contents thereof.
